DESIGN FOR A BRIDGE FOR OPHTHALMIC MOUNTINGS

Edward M. Splaine, Southbridge, Mass., assignor to American Optical Company, Southbridge, Mass., a voluntary association of Massachusetts

Application March 4, 1939, Serial No. 83,353

Term of patent 14 years

To all whom it may concern:

Be it known that I, Edward M. Splaine, a citizen of the United States of America, residing at Southbridge, in the county of Worcester and State of Massachusetts, have invented a new, original, and ornamental Design for a Bridge for Ophthalmic Mountings, of which the following is a specification, reference being made to the accompanying drawing, forming a part thereof.

Fig. I is a perspective view of a bridge for

an ophthalmic mounting embodying my new design;

Fig. II is a top plan view of the bridge shown in Fig. I; and

Fig. III is a sectional view taken on line III—III of Fig. I.

I claim:

The ornamental design for a bridge for ophthalmic mountings, substantially as shown.

EDWARD M. SPLAINE.
